UNITED STATES PATENT OFFICE.

MATHIAS CLASSEN, OF KALAMAZOO, NEBRASKA.

WINDOW.

SPECIFICATION forming part of Letters Patent No. 498,382, dated May 30, 1893.

Application filed January 21, 1893. Serial No. 459,227. (No model.)

To all whom it may concern:

Be it known that I, MATHIAS CLASSEN, a citizen of the United States, residing at Kalamazoo, in the county of Madison and State of Nebraska, have invented a new and useful Window, of which the following is a specification.

The invention relates to improvements in windows.

10 The object of the present invention is to provide a window, which will be especially adapted for car windows, and which will be air and water tight and dispense with the ordinary weights and ropes in holding the sashes at the desired adjustment.

15 The invention consists in the construction and novel combination and arrangement of parts hereinafter fully described, illustrated in the accompanying drawings and pointed 20 out in the claim hereto appended.

In the drawings—Figure 1 is an elevation, partly in section, of a window constructed in accordance with this invention. Fig. 2 is a horizontal sectional view.

25 Like numerals of reference indicate corresponding parts in all the figures of the drawings.

1 designates a spring actuated jamb strip, arranged at each side of a window 2 and having sufficient width to present its outer face to the upper and lower sashes 3 and 4 of the window, whereby it is adapted to frictionally engage the side edges of both sashes to hold the same at any desired adjustment, without 35 employing the ordinary weights and sash cords. Each jamb strip is forced outward against the edges of the sashes by spiral springs 5, arranged at intervals in pairs; and the outer face of the jamb strip is provided 40 at the middle with a vertical groove 6, in which is arranged a removable parting bead 7. The tension of the spring is regulated by adjusting screws 8, connected with each jamb strip and having their heads arranged in cylindrical recesses 9, which are located at the 45 bottom of each groove 6 beneath the parting bead; and in order to prevent the screws wearing the jamb strip, washers 10 are provided and are arranged on the screws and interposed between the heads thereof and the

jamb strip. The jamb strips are arranged between the head or top piece of the window frame and the window sill, and their upper ends 11 are bifurcated to receive a top bead 12, which is secured to the top or head piece 55 of the window frame. The spring actuated jamb strips make a window air and water tight, and prevent the same sticking by reason of any of the parts swelling in damp weather, and they dispense with the necessity 60 of employing sash weights and securely hold the sashes at any desired adjustment. The tension of the springs may be readily regulated to adjust the strips to exert the desired pressure on the sashes.

65 Although the window is particularly designed for cars, yet the improvement may be readily applied to windows of buildings.

Changes in the form, proportion and the minor details of construction may be resorted 70 to without departing from the principle or sacrificing any of the advantages of this invention. It will also be noticed that the adjusting screws limit the outward movement of the jamb strips, and prevent them from 75 being twisted when both sashes are up or down. It will also be apparent that the operative parts of the jamb strips are protected from the weather and concealed from view.

What I claim is—

80 The combination with a window, of the jamb strips arranged at the side edges of the sashes and of sufficient width to engage the latter, and provided in their engaging faces with vertical grooves and having cylindrical 85 recesses in the bottoms of the grooves, adjusting screws connected with the jamb strips and having their heads arranged in the cylindrical recesses, the removable parting beads seated in the grooves, and the springs 90 arranged at intervals in pairs back of the jamb strips, substantially as described.

In testimony that I claim the foregoing as my own I have hereto affixed my signature in the presence of two witnesses.

MATHIAS CLASSEN.
